CLAIM

The ornamental design for a control panel for a liquid waste recovery system, as shown.

DESCRIPTION

FIG. 1 is a front elevational view of a control panel for a liquid waste recovery system showing our new design;

FIG. 2 is a rear elevational view;

FIG. 3 is a bottom plan view;

FIG. 4 is a top plan view;

FIG. 5 is a right side elevational view; and,

FIG. 6 is a left side elevational view thereof.

FIG. 1

FIG. 2

FIG. 3

FIG. 4

FIG. 5

FIG. 6
